D5763

UNITED STATES PATENT OFFICE.

WILLIAM E. OSBORN, OF BROOKLYN, NEW YORK.

DESIGN FOR A HAND-STAMP.

Specification forming part of Design No. 5,763, dated April 9, 1872.

Specification describing a Design for a Hand-Stamp or Seal-Press, invented by WILLIAM E. OSBORN, of Brooklyn, in the county of Kings and State of New York.

The nature of my design is fully represented in the accompanying photographic illustration, to which reference is made.

A represents the stock or body of the stamp or press; B, the plunger-guide; C, the die-support; and D, the handle thereof. The stock A is fashioned to represent a squirrel, sitting with its fore-paws uplifted in a natural manner to hold an ear of corn or any other object which may be deemed appropriate. The tail of the animal, curled upward, as illustrated, forms a stop and support for the handle of the stamp or press. The plunger-guide B is fashioned to represent an ear of corn with some of the leaves of its husk or shuck left thereon. I contemplate, also, fashioning this plunger-guide into the form of a stick of wood or other natural object, to be held by the

squirrel. The die-support C is fashioned to represent the stump of a bush or tree cut off close to the ground, or which may be formed to represent any other natural object.

What I claim as my invention is—

1. The design for a hand-stamp or seal-press, in which the body A of the press is made in the form of a squirrel, substantially as illustrated in the accompanying photograph thereof.
2. In a design for a hand-stamp or seal-press, the plunger-guide B, formed in the shape of an ear of corn, substantially as illustrated in the accompanying photograph thereof.
3. In a design for a hand-stamp or seal-press, the die-support C, representing the stump of a tree or bush, substantially as illustrated in the accompanying photograph thereof.

W. E. OSBORN.
